ELECTRICAL CONTROLLER

Charles W. Wyman, Claremont, N. H., assignor to
 Sullivan Machinery Company, a corporation of
 Massachusetts

Application June 30, 1933, Serial No. 678,436
 Renewed October 3, 1934

20 Claims. (Cl. 201—48)

My invention relates to electrical controllers, and more particularly to electrical controllers having incorporated therein protective devices for preventing the burning of the contacts thereof.

5 An object of this invention is to provide an improved electrical controller. Another object of my invention is to provide improved electrical controlling apparatus having improved means for preventing the burning of the contacts. Still another object of my invention is to provide an improved electrical controlling apparatus providing for the cutting out of resistance in steps but having associated therewith means operative automatically to prevent the burning of the contacts 10 of the resistance controller and to localize all arcing at a device particularly designed to withstand the arcing and to extinguish the arc. Other objects and advantages of the invention will hereinafter appear.

20 In the accompanying drawing, in which, for purposes of illustration, I have shown one form which my invention may assume in practice.

Fig. 1 is a view from above, with the cover and other parts removed, of a controller in which the 25 illustrative embodiment of my invention is incorporated.

Fig. 2 is a detail view showing a portion of the automatic controlling apparatus, the view being taken from a position approximately above Fig. 1.

30 Figs. 3 and 4 are similar views, showing the parts in a different position.

Fig. 5 is a side elevational view of a portion of the mechanism shown in Figs. 2, 3 and 4.

Fig. 6 is a wiring diagram, simplified, and showing a smaller number of buttons than as illustrated in Fig. 1.

Fig. 7 is a detail view of a contact carrying member.

Referring to the drawing, 1 denotes a part of a controller box or casing, herein a plate, upon which there is mounted a plurality of contact devices, herein contact buttons, 2, 3, 4, 5, 6, 7, 8 and 9, the contacts 2 and 3 being dead contacts, and contacts 4 to 9, inclusive, each having connected between them a stage of starting resistance. There is also mounted upon the plate 1 a series of buttons 10, suitably connected through blow-out coils 11 with the contactor buttons 4 to 9 inclusive, and adapted to protect the main contactor buttons from arcing, by coaction with a roller 12 which is supported by the controller arm 13 in adjacency to the main moving contact member 14. Still further to protect the controller box from the detrimental effects of arcing, I have provided means for automatically breaking the circuit at

a point outside the controller box whenever the controller arm is moved toward "off" position.

Referring now to the wiring diagram, the controller arm is indicated at 13, the resistance controlled by the starting box at 15; the motor to be controlled has its armature represented at A, its series field at SeF, and its shunt field at ShF. The supply lines are indicated at 16 and 17, and at 18 is indicated a main circuit breaking contactor having a controlling coil 19 and a pilot switch 20 whose construction I shall shortly describe in detail.

Referring now particularly to Fig. 2, it will be noted that the pilot switch mechanism, which is generally designated 20, is supported upon a block 15 21 secured to the plate 1 of the controller. This block provides, upon its upper side, a surface 22 upon which, through a pin 23, a contact carrying arm member 24 is oscillatably supported. The arm 24 is slotted, as at 25, and is provided in its lower side with a recess 26 within which a spring 27 is housed. The spring 27 is so related to the recess and to the pin 23 that the contact carrying arm 24 is always yieldingly but firmly pressed toward the main controller arm 13. The end of the arm 24 toward the controller arm is formed on an arc struck from the axis of the pin 23, and is adapted to cooperate with a cylindrical surface 29 formed upon a portion of the controller arm 13; the yielding pressure of the arm 24, pressed by the spring 27, against the surface 29 causing the contact carrying block 24 to be swung, when free to move, in an opposite direction to the direction of rotation of the main controller arm 13 as the latter is moved about its pivot. A stop pin 28 on the block 21 and arranged in the path of movement of the arm 24, prevents the arm 24 from swinging out too far, thereby always maintaining the arm 24 in frictional contact with the surface 29 on the controller arm. The block 24 30 carries a yieldably mounted contact member 30 which is adapted to cooperate with a stationary contact 31 carried upon an upstanding support 32 secured to the block 21. The contact members 30 and 31, when closed, are adapted to energize, 35 through suitable connections, the operating coil 19 of the contactor 13, and when separated, to effect deenergization of the coil 19.

Pivoted upon a horizontal pin 34 upon an upstanding wall of the block 21, is a latch member 35; and a spring 36 is positioned within a recess 37 in the latch member and normally tends to raise the free end of the latch member. This latch member 35 has an upstanding portion 38 which is adapted, in the "off" position of the contact 55

carrying member 24, to move into a position which will prevent the movement of the contact member 24 to a position in which the contact 30 can engage the contact 31. The controller member 13 5 carries upon its lower surface a strip of suitable material 39 providing a camming surface which is adapted to engage a beveled or curved upper camming surface 40 formed at one end of the member 35. As the controller arm 13 reaches 10 "off" position, it will be noted that its position relative to the member 35 is then such that the latter is approximately tangential to a circle concentric with the axis of rotation of the controller arm 13, at a point in such circle where a radial 15 line extending along the arm 13 cuts the circle, so that when the controller arm is in "off" position the strip 39 overlies and holds depressed the outer or free end of the latch member 35.

It will be evident that, if desired, the pilot and 20 main contactors could be replaced by a main contactor suitably actuated and controlled similarly to the pilot.

With the description given, the mode of operation of this apparatus will be readily understood. 25 Referring to Fig. 1, it will be noted that the controller arm 13 is in "off" position; and referring to Fig. 2 it will be apparent that in the position of the parts shown in Fig. 1 the outer or free end of the latch member 35 is depressed, as above 30 indicated, and the projection 38 is held in a position such that it cannot interfere with arcuate movement of the contact carrying member 24. Upon starting of movement of the controller arm 13 toward its position in which it first connects 35 the motor through the full resistance, to the line, the arcuate surface 29 heretofore referred to, by frictional engagement with the arcuate end of the contact carrying member 24, will move the contact carrying member 24 to bring the contact 30 40 into engagement with the contact 31. This will immediately energize the coil 19 and close the contactor 18. During further movement toward the full "on" position of the controller arm 13, the frictional reaction of the surface 29 upon 45 the end contact carrying member 24 will simply tend to press the contacts 30 and 31 yieldingly together. The contactor 18 is closed before the first "live" button 4 is reached by the member 14.

As soon as the contact carrying arm 13 is moved 50 sufficiently far to effect the connection of the motor, through the resistance, with the line, the strip 39 will run off the full width portion of the latch member 35. Thereupon the spring 36 would be effective to move the latch member upwardly 55 and bring the projection 38 into the position shown in Fig. 4, were it not for the fact that the projection is confined in its lower position by engagement with the lower surface of the member 24, which was moved over it when switch member 30 was moved to closed position. Let the operator, however, attempt to move the controller arm 13 toward "off" position, and the frictional 60 engagement of the surface 29 with the arcuate end of the contact carrying member 24 will immediately throw the contact 30 into open position, thereby causing contacts 18 to open, and simultaneously, due to the movement of the member 24 to such a position that this is possible, the latch portion 38 will spring up into the path of arcuate 65 movement of the member 24 and prevent closure again of the contact 30 in the event of a resumed forward direction of movement of the controller arm. To be able again to close the pilot switch it will be necessary to move the arm 13 back to 70 depress the tongue 35, and thereafter reversal 75

of movement of arm 13 will be effective to drag the arm 24 over the depressed latch portion 38 and reclose the pilot. Obviously any reverse movement of lever 13 in an effort to shut off the current will result in opening the pilot switch, and 5 so shut off the main line contactor, and thus prevent burning of the buttons 4 to 9 inclusive.

From the foregoing description it will be evident that I have provided a very simple but effective arrangement for protecting a starting rheostat—one in which the burning of rheostat contacts is prevented; and that a most inexpensive type of pilot mechanism, having a positive lock for holding it in open position when necessary, is associated in a most desirable manner with the 15 operating mechanism of the rheostat.

While I have in this application specifically described one form which my invention may assume in practice, it will be understood that this form of the same is shown for purposes of illustration, 20 and that the invention may be further modified and embodied in various other forms without departing from its spirit or the scope of the appended claims.

What I claim as new and desire to secure by 25 Letters Patent is:

1. In an electric controlling apparatus, a controller arm, a pilot switch, means movable to close said pilot switch on movement of said controller arm in a circuit-establishing direction, and means operative on reverse movement of said arm to open and lock in open position said pilot switch, said locking means including a latch occupying one position when effecting its holding function and a different position to effect release and held 35 out of said first mentioned position whenever said pilot switch is closed.

2. In an electric controlling apparatus, a controller arm, a switch, means movable to close said switch on movement of said controller arm in a 40 circuit-establishing direction, and means operative on reverse movement of said arm to open and lock in open position said switch, said locking means including a latch occupying one position when effecting its holding function and a 45 different position to effect release and held out of said first mentioned position whenever said switch is closed, by said movable switch-closing means.

3. In an electric controlling apparatus, resistance controlling means including a controller arm, a main circuit breaking contactor, controlling means for the latter including a pilot switch, means moving with said controller arm from "off" 50 position for moving said pilot switch to closed 55 position, and latch means releasable only by movement of said arm in the reverse direction and released when said arm is in full "off" position, for locking said pilot switch in open position when opened. 60

4. In an electric controlling apparatus, resistance controlling means including a controller arm, a main circuit breaking contactor, controlling means for the latter including a pilot switch, means moving with said controller arm for moving 65 said pilot switch to closed position, and latch means releasable only by movement of said arm to its extreme position in the reverse direction, for locking said pilot switch in open position when opened, while said controller arm is in a circuit 70 establishing position.

5. In an electric controlling apparatus, resistance controlling means including a controller arm, a main circuit breaking contactor, controlling means for the latter including a pilot switch, 75

means moving with said controller arm for moving said pilot switch to closed position, and latch means held in releasing position when said pilot switch is closed, and, when operated, releasable 5 only by movement of said arm to its extreme position in the reverse direction, for locking said pilot switch in open position when opened.

6. In an electric controller, a resistance controlling means including a controller arm, a main 10 contactor, an operating circuit for the latter including a pilot switch, a pilot switch controlling latch precluding closing movement thereof except during the initial portions of the movements of said controller arm from "off" to "on" position, 15 pilot closing means including a part movable to effect pilot closure and a cooperating part moving with said arm and providing, when said arm moves in horizontal planes, a vertical wiping surface engaging said first mentioned part and constituting moving means therefor, and latch controlling means including a wiping surface moving 20 with said arm and extending horizontally when said arm moves in horizontal planes and a portion whose movements control latch position engaged and controlled by said horizontal wiping surface.

7. In an electric controller, resistance controlling means including a pivoted controller arm, a switch lever pivotable about an axis parallel to the pivot of said controller arm, frictionally engaged surfaces associated with said arm and switch lever respectively whereby movements of said arm effect movements of said switch lever, and latch means governed by said arm only during the portions of movement of the latter when no circuit establishing connections are made thereby, said latch means moved to releasing position as said arm approaches full "off" position and held in such position until material reverse 35 movement of said arm takes place.

8. In an electric controller, resistance controlling means including a pivoted controller arm, a switch lever pivotable about an axis parallel to the pivot of said controller arm, frictionally engaged surfaces associated with said arm and switch lever respectively whereby movements of said arm effect movements of said switch lever whenever the latter is free to move and thereafter slipping takes place, and latch means governed 45 by said arm only during the portions of movement of the latter when no circuit establishing connections are made thereby, and released from control prior to the establishment of any circuit by the latter, and rendered inoperative again 50 when, but only when, said arm is again in circuit interrupting position.

9. In an electric controller, resistance controlling means including a pivoted controller arm, a switch lever pivotable about an axis parallel to the pivot of said controller arm, frictionally engaged surfaces associated with said arm and switch lever respectively whereby movements of said arm effect movements of said switch lever, and latch means governed by said arm only during the portions of movement of the latter when no circuit establishing connections are made thereby, and released from control by said arm prior to the establishment of any circuit by the latter, and rendered inoperative again by said arm when, but only when, said arm is again in circuit interrupting position, said latch means underlying said switch lever and held immovable by the latter in certain positions thereof.

75 10. In an electric controller, resistance con-

trolling means including a pivoted controller arm, a switch lever pivotable about an axis parallel to the pivot of said controller arm, frictionally engaged surfaces associated with said arm and switch lever respectively whereby movements of said arm effect movements of said switch lever, and latch means governed by said arm only during the portions of movement of the latter when no circuit establishing connections are made thereby, and released from control by said arm prior to the establishment of any circuit by the latter, and rendered inoperative again when said arm is again in circuit interrupting position, said latch means underlying said switch lever and held immovable by the latter, when the latter is in closed circuit position but movable to hold said switch lever when the latter is in open circuit position.

11. In an electric controlling apparatus, resistance introducing and eliminating means, a switch, means operative to effect closure of said switch on operation of said first-mentioned means to establish a circuit including resistance, and means operative on operation of said first mentioned means to reintroduce resistance once eliminated thereby, to open and lock in open position said switch, said locking means including a catch maintained in retracted position when said switch is in closed position.

12. In an electric controller, resistance controlling means including a pivoted controller arm, a switch lever, frictionally engaged surfaces associated with said arm and switch lever respectively whereby movements of said arm effect movements of said switch lever, and latch means governed by said arm only during the portions of movement of the latter when no circuit establishing connections are made thereby for unlatching said latch means when said arm is in full "off" position.

13. In an electric controller, resistance controlling means including a pivoted controller arm, a switch lever, frictionally engaged surfaces associated with said arm and switch lever respectively whereby movements of said arm effect movements of said switch lever, and latch means governed by said arm only during the portions of movement of the latter when no circuit establishing connections are made thereby, and released from control prior to the establishment of any circuit by the latter, and rendered inoperative again by said arm when, but only when, said arm is again in circuit interrupting position.

14. In an electric controller, resistance controlling means including a pivoted controller arm, a switch lever, frictionally engaged surfaces associated with said arm and switch lever respectively whereby movements of said arm effect movements of said switch, and latch means governed by said arm only during the portions of movement of the latter when no circuit establishing connections are made thereby, and released from control by said arm prior to the establishment of any circuit by the latter, and rendered inoperative again when said arm is again in circuit interrupting position, said latch means underlying said switch lever and governed by the lower surface of the latter.

15. In an electric controller, resistance controlling means including a pivoted controller arm, a switch lever, frictionally engaged surfaces associated with said arm and switch lever respectively whereby movements of said arm effect movements of said switch lever, and latch means governed by said arm only during the portions

of movement of the latter when no circuit establishing connections are made thereby, and released from control prior to the establishment of any circuit by the latter, and rendered inoperative again by said arm only when said arm is again in circuit interrupting position, said latch means underlying said switch lever and held inoperative thereby, when the latter is in closed circuit position but movable to hold said switch lever when said arm is in open circuit position.

16. In an electric controller, resistance controlling means including a movable element whose position alters with the variation in effective resistance, a switch element, frictionally engaged surfaces associated with said elements respectively whereby movement of the first-mentioned element effects movement of the second when the latter is free to move, and latch means governed by movement of the first-mentioned element but only during the portions of movement of the latter when no circuit-establishing connections are made thereby, and released from control prior to the introduction of any resistance by said resistance controlling means and rendered inoperative again only when said resistance controlling means is in open circuit position.

17. In an electric controlling apparatus, a controller element, a switch element, means operative to close said switch element on movement of said controller element in circuit-establishing direction, and means including a latch held in open position during such movement of said controller element and operative on reverse movement of said controller element to move said switch element to open circuit position and preclude further control thereof by said controller element until the latter has been brought back to open circuit position.

18. In an electric controlling apparatus, a controller element, a switch element, means operative to close said switch element upon movement of said controller element in circuit-establishing direction and to open said switch element upon opposite movement of said controller element, and means operative to preclude reclosure of said

switch until said controller element is returned to its full "off" position including latch means opened by said controller element and held open by said switch element during normal current supply through said apparatus.

19. In an electric controller, resistance controlling means including a pivoted controller arm, a switch lever, frictionally engaged surfaces associated with said arm and switch lever respectively whereby movements of said arm effect movements of said switch lever, and latch means governed by said arm only during the portions of movement of the latter when no circuit establishing connections are made thereby, and between the establishment of a circuit by said arm and reverse movement of the latter governed by said switch lever, and released from control by said arm prior to the establishment of any circuit by the latter, and rendered inoperative again by said arm only when said arm is again in circuit interrupting position, said latch means underlying said switch lever and governed by the lower surface of the latter.

20. In an electric controller of the type in which provision is made for establishing a circuit through a resistance and then cutting out the resistance, resistance controlling means including a swingable controller arm, a switch closable to effect current supply through the resistance, coacting surfaces, one movable upon swinging movement of said arm and the other movable by said first-mentioned surface, for closing and opening said switch by movements of said arm, a latch for controlling switch movements operative to preclude closing of the switch except in positions of said arm in which no resistance has been cut out, and coacting camming surfaces one movable upon movement of said arm and one movable with said latch for controlling the latter, one of said sets of coacting surfaces having its elements extending generally radially of the axis of arm swing and the other set having its elements extending generally longitudinally of such axis.

CHARLES W. WYMAN. 45

CERTIFICATE OF CORRECTION.

Patent No. 2,061,887.

November 24, 1936.

CHARLES W. WYMAN.

It is hereby certified that error appears in the printed specification of the above numbered patent requiring correction as follows: Page 3, second column, lines 57 and 59, claim 14, after "switch" insert the word lever; and line 65, before "only" insert the words by said arm; page 4, first column, line 9, claim 15, after "position insert a comma; and that the said Letters Patent shculd be read with these corrections therein that the same may conform to the record of the case in the Patent Office.

Signed and sealed this 8th day of June, A. D. 1937.

Henry Van Arsdale

(Seal)

Acting Commissioner of Patents.
